(57) CLAIM

The ornamental design for a storage box as shown.

DESCRIPTION

FIG. 1 is a front, right, and top perspective view of a storage box showing my new design;

FIG. 2 is a rear, left, and bottom perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof.
